UNITED STATES PATENT OFFICE.

OTTO S. KALLMAN, OF MINNEAPOLIS, MINNESOTA.

TAP AND REAMER CHUCK.

1,421,949.

Specification of Letters Patent.

Patented July 4, 1922.

Application filed February 20, 1920. Serial No. 360,240.

To all whom it may concern:

Be it known that I, OTTO S. KALLMAN, a citizen of the United States, residing at Minneapolis, in the county of Hennepin and State of Minnesota, have invented certain new and useful Improvements in Tap and Reamer Chucks, of which the following is a specification.

This invention relates to chucks, and the 10 primary object of the invention is to provide an improved chuck especially adapted for holding taps and reamers, but which is capable of holding other tools, and which is so constructed that taps of various sizes may 15 be held.

Another object of the invention is to provide an improved tap embodying an adjustable disc having a plurality of different sized square recesses formed therein, any one of 20 which is adapted to be brought into alignment with the tap receiving opening, so that different sized taps having different sized squared terminals may be secured in the chuck.

25 A further object of the invention is the provision of a chuck having means for receiving the different sized squared terminals of taps and an improved means located below the means for receiving the squared tap terminals for adjustably engaging and clamping the shanks of the taps.

30 A further object of the invention is to provide an improved clamp which is capable of holding reamers used in hand work, 35 the chuck body forming an efficient handle for the reamer.

40 A still further object of the invention is to provide an improved chuck for holding taps and reamers of various sizes which is durable and efficient in use, one that is simple and easy to manufacture, and one which can be placed upon the market at a reasonable cost.

45 Other objects and advantages of the invention will appear from the following detailed description, taken in connection with the drawings, forming a part of this specification, in which drawings:

50 Figure 1 is an elevation of the improved chuck.

Figure 2 is a longitudinal vertical section through the chuck taken on the line 2—2 of Figure 1.

55 Figure 3 is a bottom plan view of the chuck.

Figure 4 is a vertical longitudinal section

through the chuck taken on the line 4—4 of Figure 2.

Figure 5 is a transverse section through the chuck taken on the line 5—5 of Figure 2. 60

Figure 6 is a transverse section through the chuck taken on the line 6—6 of Figure 2.

Figure 7 is a transverse section taken on the line 7—7 of Figure 2.

Figure 8 is a transverse section taken on the line 8—8 of Figure 2, and

Figure 9 is an enlarged detail elevation of the spring fingers for holding the jaws in operative position.

Referring to the drawings in detail, where- 70 in similar reference characters designate corresponding parts throughout the several views, the numeral 10 indicates the improved chuck which includes the tapered shank 11 having the flattened terminal 12 of the ordinary configuration. The lower end of the shank 10 is adapted to be connected to the solid cylindrical body 13 of the chuck by a removable collar 14, which includes an annular attaching flange 15, which is adapt- 80

16. The collar 14 is provided with an inwardly extending annular peripheral retaining flange 17, which is adapted to en- 85 gage the outer surface of the annular rib 18 formed on the lower end of the tapered shank 11. The extreme lower end of the tapered shank 11 is provided with a depending polygonal nose 19, which is adapted to fit in a polygonal opening 20 formed in the upper face of the chuck body 13 at the central portion thereof. The chuck body 13 intermediate its ends is provided with a diametrically extending slot 21, which is adapt- 90

95 ed to receive the disc 22. The periphery of the disc 22 is provided with a plurality of inwardly extending polygonal recesses 23, any one of which is adapted to be brought into alignment with the longitudinally ex- 100 tending bore 24 formed in the chuck body. The different sized recesses 23 formed in the periphery of the disc 22 are adapted to receive the squared terminals of the taps and the like, and by mounting the disc so that 105 any one of the recesses may be brought into alignment with the bore 24 of the body, various sized taps can be accommodated.

The disc 22 is rotatably mounted in the chuck body 13 by means of a diametrically 110 extending pin or shaft 25, which has its terminals rotatably mounted in suitable

openings 26 formed in the chuck body. The disc 22 is provided with a concentric opening 27 for the reception of the pin or shaft 25 and the disc is secured to the pin or shaft 25 by a suitable key 28. One terminal of the pin or shaft 25 is provided with an enlarged head 29, which is fitted in the enlarged portion 30 of one of the openings 26 provided for rotatably supporting the pin or shaft 25. The head 29 of the pin or shaft 25 is provided with a slot 31, for the reception of a screw driver or the like so as to permit the pin or shaft to be turned for bringing any one of the desired recesses 23 into alignment with the bore 24. The outer surface of the body 13 is provided with a casing or sleeve 32, which is secured to the body by suitable removable fastening elements 33. The sleeve 32 forms means for preventing the accidental displacement of the pin or shaft 25. The sleeve 32 is provided with an opening 34, which is in direct alignment with the head 29 of the pin 25. The opening 34 is formed relatively smaller than the head 29 so as to prevent the head 29 from riding on through the opening. The inner surface of the opening 34 adjacent to the upper end thereof is provided with a cut 35 which acts as an indicator to cooperate with the marks 36 inscribed on the outer face of the head 29 of the pin. The marks 36 inscribed on the head 29 of the pin 25 conform to the recesses 23 formed in the periphery of the disc 22, and the marks indicate the size of the said recesses. By rotating the head 29 and bringing the mark indicating the desired size of the recess to be used in connection with the tap into direct alignment with the indicator 35, the said recess 23 is brought into registration with the bore 24 of the chuck body 13.

A leaf spring 37 is provided for holding the disc 22 against accidental turning movement in the chuck body when one of the recesses 23 has been brought into registration with the bore 24. The spring 37 has its lower end provided with an inwardly extending tooth 38 which is adapted to detachably fit in any one of a plurality of notches 39 formed in the periphery of the disc 22. A notch 39 is provided for each one of the recesses so as to effectively hold any one of the recesses in alignment with the bore 24. The upper end of the spring 37 is provided with an angular attaching foot 40 which is secured to the upper wall of the slot 21 by a suitable removable fastening element 41.

The chuck body 13 is provided with a plurality of radially extending slots 42' which extend outwardly from the bore 24 and these slots 42' are adapted to snugly receive the jaws 42 which are adapted to engage and clamp the shank of a tap, to firmly hold a tap against accidental displacement from

the chuck body. Each of the jaws 42 is pivotally mounted upon a pin 43 which extends through the jaw and into the chuck body. The portions of the jaws 42 extending above the pivot pins 43 are provided with inclined outer surfaces 44 which are adapted to be engaged by the inner ends of leaf springs 45, which are provided with enlarged attaching feet 46, having openings 47 provided therein for the reception of fastening elements 48, which extend into the chuck body. The leaf springs 45 tend to swing the jaws 42 on the pivot pins 43 and hold the lower ends thereof out of the bore 24. The jaws 42 directly below the pivot pins 43 are notched as at 49 and these notches extend in direct alignment with the annular groove 50 formed in the chuck body 13. The inner wall of the annular groove 50 is provided with threads on which is fitted the internally threaded ring 51, which forms means for moving the lower end of the jaws 42 into the bore 24 against the tension of the leaf spring 45. The inner surface of the jaws 42 adjacent to the lower ends thereof are provided with inwardly extending jaw faces 52, which may be serrated if so desired for engaging a shank of a tap. The outer surface of the jaws 42 directly in rear of the jaw faces 52 are provided with downwardly and outwardly inclined shoulders 53 which are adapted to be engaged by the lower conical wall 54 formed on the inner surface of the adjusting ring 51. It can be seen that by turning the adjusting ring 51, in one direction, the conical wall thereof will be forced into engagement with the inclined surface of the jaws 42 and thus force the jaw faces 52 into bore 24 for engaging a tap positioned therein. The outer surface of the adjusting ring 51 may be provided with suitable inwardly extending openings 55 for the reception of a spanner wrench to facilitate the turning thereof, or the entire outer surface of the ring can be serrated or milled so as to permit a firm hold to be obtained thereon by the hand of the user. A cap 56 is provided for the lower end of the body and is detachably secured thereto by inwardly extending fastening elements 57. The lower wall of the cap is provided with a concentric opening 58, which is in direct alignment with the bore 24 of the chuck body 13.

In operation of the improved chuck, the ring 51 is rotated in the desired direction so as to retract the jaw faces 52 out of the bore 24 and the disc 22 is rotated by means of the slot 31 of the head 29 of the pin 25 until a recess 23 of the desired size is brought into alignment with the bore 24. A tool is then inserted in the bore and the square end thereof is inserted into the opening 23. The ring 51 is then turned in a reverse direction so as to force the jaw faces 52 of the jaws 42

42 into tight engagement with the shank of the tool to prevent accidental displacement thereof. The shank of the chuck is then inserted into the machine in the ordinary 5 manner.

From the foregoing description it can be seen that an improved chuck is provided for holding taps of various sizes which is of exceedingly durable and efficient construction 10 and which will effectively accomplish the purpose intended.

Changes in details may be made without departing from the spirit or scope of the invention; but,

15 I claim:

1. A chuck, comprising a body having a tool shank receiving opening formed therein, means arranged in the body having a plurality of different sized openings therein 20 arranged to receive the inner ends of a tool shank, and means carried by said body and projecting into said tool shank receiving opening therein, for clamping a tool.

2. An improved chuck comprising a body 25 having a tool shank receiving opening formed therein, the body having a diametrically extending slot formed therein directly above the bore, a pin rotatably mounted in the body and extending through said slot, a disc keyed 30 to said pin having a plurality of different sized polygonal openings formed in the periphery thereof, means for turning the pin for rotating the disc to bring any one of the openings formed therein into alignment with the 35 tool shank receiving opening, the disc having a plurality of spaced notches, a leaf spring carried by the body, and a tooth formed on the leaf spring for engaging in any one of the notches.

40 3. A chuck comprising a body having a tool receiving opening formed therein, a member rotatably mounted in the body having a plurality of different sized polygonal openings formed therein arranged to be 45 brought into registration with the tool receiving opening, and adjustable jaws carried by the body and arranged to be brought into and out of the tool receiving opening below the rotatable member.

50 4. A chuck comprising a body having a tool shank receiving opening formed therein, a rotatable member arranged in the body

having a plurality of different sized polygonal openings formed therein arranged to be brought into alignment with the tool shank receiving openings, a plurality of pivoted jaws carried by the body and arranged below the rotatable member, the jaws being adapted to extend into the tool shank receiving opening, and means for adjusting 60 the jaws in relation to the tool shank receiving opening.

5. An improved chuck comprising a body having a tool shank receiving opening formed therein, a member rotatably mounted in the body having a plurality of polygonal openings formed in the periphery thereof arranged to be brought into alignment with the tool shank receiving opening, a plurality of pivoted jaws carried by the 70 body arranged below the rotatable member, said jaws being adapted to extend into the tool shank receiving opening, spring means engaging the jaws to normally hold the same out of the tool shank receiving opening, and 75 means for moving the jaws into the tool shank receiving opening.

6. A chuck comprising a body having a diametrically extending slot formed therein, a pin rotatably carried by the body and extending through the slot, a disc keyed to the pin having a plurality of different sized polygonal openings formed in the periphery thereof, a plurality of pivoted jaws arranged below the disc, a sleeve arranged around the 85 body, the lower end of the body being reduced and externally screw threaded, the lower terminals of the jaws having inclined outer faces, and a ring fitted on said threaded reduced terminal of the body and arranged to engage the inclined faces of the 90 jaw.

7. A chuck comprising a body portion having a tool receiving opening therein, a disc having a plurality of different sized tool receiving recesses in its periphery, a shaft keyed to said disc and rotatably supported within said body portion, in such manner that any one of said recesses in said disc may align with said body opening, jaws pivoted within said body, and means for advancing said jaws to project into said body opening for clamping a tool.

OTTO S. KALLMAN.
